GARBAGE CAN AND COVER KEEPER

Ronald G. Blank, Robbinsdale, Minn.

Application May 21, 1947, Serial No. 749,415

5 Claims. (Cl. 248—146)

1

My invention relates to improvements in garbage can and cover keepers.

An object of this invention is to provide novel means for keeping a garbage can in a predetermined position and positively preventing the same from being upset.

Another object of this invention is to provide novel means for anchoring the cover of a garbage can and for holding the same in a raised position when removed from the garbage can.

A further object of this invention is to provide novel keeper means that is readily adjustable for garbage cans and their covers of different sizes.

Other objects of this invention will be apparent from the following description, reference being had to the drawing.

To the above end, generally stated, the invention consists of the novel devices and combination of devices hereinafter described and defined in the claims.

In the accompanying drawing, which illustrates the invention, like characters indicate like parts throughout the several views.

Referring to the drawing:

Fig. 1 is an elevational view of the invention, together with a garbage can and cover, some parts being shown in different positions by means of broken lines;

Fig. 2 is a fragmentary view partly in elevation and partly in central vertical section, with the keeper arm and cover raised, as shown by broken lines in Fig. 1;

Fig. 3 is a fragmentary detail view partly in elevation and partly in section taken on the line 3—3 of Fig. 2;

Fig. 4 is a detail view partly in plan and partly in section taken on the line 4—4 of Fig. 1;

Fig. 5 is a view partly in plan and partly in section taken on the line 5—5 of Fig. 1; on a reduced scale; and

Fig. 6 is a fragmentary view partly in elevation and partly in section showing a different mounting of the keeper.

The numeral 7 indicates a garbage can having a pair of hinged loop-like side handles 8 and a displaceable cover 9 provided with a fixed handle 10 on the top thereof.

Referring now in detail to the invention shown in Figs. 1 to 5, inclusive, the numeral 11 indicates a heavy pear-shaped cement base for the garbage can 7. On the rear or small end portion of the base 11 is a tubular post 12 connected to a horizontal pipe section 13 by an elbow 14. This pipe section 13, elbow 14 and connected end portion of the post 12 are embedded in the base 11

2

and rigidly hold the post 12 in an upright position back of the garbage can 7.

Forming an extension of the post 12 is a body member 15, in the form of a channel bar, the flanges of which are turned forwardly. The post 12, at its upper end portion, extends into the body member 15 at its lower end portion and is detachably secured thereto by a nut-equipped bolt 16. This bolt 16 extends through aligned holes in the post 12 and the back of the body member 15.

The garbage can 7 is detachably connected to the post 12 by a keeper 17 comprising a horizontally disposed member 18 having at one end a long finger 19 and at its other end a short finger 20. These fingers 19—20 extend, one upwardly and the other downwardly. The keeper 17 is reversible to position either one of the fingers 19—20 upwardly and the other downwardly. The keeper 17 is formed of a single flat bar and the member 18 rests on the top of the post 12 and extends outwardly therefrom between the flanges of the body member 15.

When the keeper 17 is positioned, as shown in the drawing, its long finger 19 projects upwardly through one of the garbage can handles 8, and the short finger 20 is interposed between the post 12 and the back of the body member 15. The keeper 17 is rigidly secured to the post 12 by the bolt 16 which extends through a hole 21 in the short finger 20. When the keeper 17 is reversed from its position shown in the drawing, the bolt 16 extends through a hole 22 in the long finger 19.

The purpose of making the fingers 19—20 of different length is to accommodate the keeper 17 to garbage cans in which the handles are positioned different distances from the bottom of said can.

To detach the garbage can 7 from the keeper 17, it is only necessary to lift the same sufficiently to carry the handles 8 above the long finger 19 or the short finger 20 when the keeper 17 is reversed.

The garbage can cover 9 is attached to a pivoted keeper arm 23 on the member 15 and held raised thereby, when lifted from the garbage can 7. This keeper arm 23 is in the form of a channel bar, the flanges of which are turned downwardly. The keeper arm 23, at its inner end portion, extends between the flanges of the body member 15 and is connected thereto by a pivot pin 24. This pivot pin 24 extends through vertical slots 25 in the flanges of the body member 15 and longitudinal slots 26 in the flanges of the keeper arm 23.

The cover 9 is adjustably and detachably secured to the keeper arm 23 by positioning its

handle 10 between the flanges of said arm and connecting the same thereto by a pair of nut-equipped bolts 27. These bolts 27 extend through any two pairs of aligned holes 28 in the flanges of the keeper arm 23 and the handle 10 on the cover 9. The longitudinally spaced holes 28 permit the cover 9 to be attached to the keeper arm 23 in different adjustment from the body member 15. On the top of the keeper arm 23 is a handle 29 by which the arm may be manipulated.

To remove the cover 9 from the garbage can 7, the arm 23 is swung upwardly by means of its handle 29 and then moved endwise downwardly with its lower end positioned against the back of the body member 15, see Fig. 2. The slots 25 and 26 permit this adjustment of the keeper arm 23. The inclination at which the cover 9 may be held suspended by the keeper arm 23 may be varied, at will, by moving the arm 23 different distances downwardly in the body member 15.

Referring to the invention as mounted in Fig. 6, the base 11 and the post 12 are dispensed with and body member 15 secured to the side of a building 30 by a pair of screws 31, one of which extends through the back of said member in place of the bolt 16, and the other extends through a hole 32 in the back of the body member 15 near the upper end thereof.

From a broad viewpoint, the post 12 and the body member 15 may be treated as a single post.

Obviously, from the above description, it is evident that the keeper 17 will hold the garbage can in definite position relative to the post and positively holds the same from being upset. The keeper arm 23 likewise anchors the cover of the garbage can to the post, and it is only necessary to lift said arm to remove the cover from the can and hold the same suspended over said can while depositing garbage therein or when removing the can to empty the same. When replacing the cover on the can, a slight outward endwise movement of the keeper arm 23 will release the same from its engagement with the back of the body member 15 to permit the same to be lowered.

When the keeper is mounted, as shown in Fig. 6, a suitable base, not shown, may be provided for the garbage can.

The word "handle" is herein used in a broad sense to cover any similar member on the side of a garbage can to attach the keeper thereto.

From what has been said, it will be understood that the invention described is capable of modification as to details of construction and arrangement within the scope of the invention herein disclosed and claimed.

What I claim is:

1. In a device of the class described, an upright channeled body member applicable to a fixed support, a horizontally disposed keeper arm, one end portion of which extends between the flanges of the body member, said body member having up-

right slots in its flanges, said keeper arm having longitudinal slots in its flanges intersecting the slots in the body member, a pivot pin extending through said intersecting slots, and means on the keeper arm for detachably securing the cover of a garbage can to the keeper arm, said keeper arm being free for endwise sliding engagement with the back of the body member to hold the same in a raised inclined position.

2. A keeper for a garbage can comprising a bar having its end portions laterally offset, the one from the other, and means for attaching the lower end portion of the bar to a support, the upper end portion of the bar being insertable through a handle on the side of the garbage can at the time the garbage can is being lowered onto a support.

3. A keeper for a garbage can comprising an endwise reversible bar having its end portions laterally offset, the one from the other, one of said portions being relatively long and the other relatively short, and means for attaching the lower end portion of the bar to a support, the upper end portion of the bar being insertable through a handle on the side of a garbage can at the time the garbage can is lowered onto a support.

4. In a device of the class described, an upright channel bar applicable to a support, a horizontally disposed arm having one of its end portions extended between the flanges of the channel bar and attached thereto for compound pivotal and endwise movement, said arm being movable into a raised inclined position with its inner end engaging the channel bar as a base of resistance and holds the arm where positioned, and means for attaching the cover of a garbage can thereto.

5. The structure defined in claim 4, further including a keeper for the garbage can in the form of an upright bar, the end portions of which are laterally offset the one from the other, the lower end portion of the bar being between the flanges of the channel bar and rigidly secured relative to said bar, the upper end portion of the bar being insertable through a handle on the side of the garbage can at the time the garbage can is being lowered onto a support.
